Carpets

No. 5,636.

Mar. 5, 1872.

UNITED STATES PATENT OFFICE.

ARCHIBALD McCALLUM, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,636, dated March 5, 1872.

Specification describing a Design for Carpets, invented by ARCHIBALD McCALLUM, of Halifax, in the county of York, England.

This invention relates to a new design for carpets and other fabrics; and consists in the following details of ornamentation, and in their combination with each other, to wit: First, in the peculiar design of irregular octagons, A, each of which has tufts *a a* at the ends of the long sides, and embraces a decorative center, *b*; second, in the peculiar design of the irregular hexagons B, which have tufts at the junctions of the short sides, as shown; and, thirdly, in the design for the ground-work C, consisting of small quatrefoils at regular distances apart, and of lines connecting the same,

and colored spots and crosses between the lines, as shown.

I claim as my invention—

1. The design of the irregular octagon A, as described.
2. The design of the irregular hexagon B, as described.
3. The design of the ground-work C, as described.
4. The design for a carpet, consisting of the figures A, B, and ground-work C, all combined as described.

ARCHIBALD McCALLUM.
